UNITED STATES PATENT OFFICE.

EUGENE M. STARN, OF BUTTE, MONTANA.

MOUNTING FOR ROLLER-SHADES.

1,232,729.

Specification of Letters Patent.

Patented July 10, 1917.

Application filed August 26, 1916. Serial No. 117,061.

To all whom it may concern:

Be it known that I, EUGENE M. STARN, a citizen of the United States, and a resident of Butte, in the county of Silverbow and 5 State of Montana, have invented a certain new and useful Improvement in Mountings for Roller-Shades, of which the following is a specification.

My present invention relates to mountings 10 for roller shades of that type now in common use, embodying a roller or elongated cylindrical body, with a stub spindle at one end and a spring in the hollow of the roll at the other end thereof including a catch mechanism 15 for holding the same in an adjusted position, said catch mechanism including a key, polygonal in cross-section, which protrudes at the end of the cylindrical body or roller at its end opposite said stub spindle. 20 The principal objects of my invention are to provide a mounting of the character described which may be easily disposed into operative relation to the roller shade without alteration of the same, and easily 25 applied to the window casing without destroying the architectural effect of such casing, from an esthetic standpoint, and without marring or in any way defacing the window casing; to provide mountings of the character 30 described which will enable the cylindrical body or roller to be quickly disposed at any height with respect to the window sash affording ventilation at the upper portion of the window, if desired, without the 35 shade obstructing free movement of the air therethrough; and, to provide mountings of the character described which may be placed into operative relation to the roller shade and window casing without the use of tools 40 or other accessories, enabling the person to quickly align the shade with the uprights or jambs of the casing if it is not primarily aligned when first placed.

Other objects of my invention will appear 45 in the following detailed description, taken in connection with the accompanying drawing, forming a part of this specification, and in which drawings:

Figure 1 is an elevation of the upper portion 50 of a window casing showing a roller shade in operative relation thereto and supported by mountings embodying my invention.

Fig. 2 is an enlarged detailed view, partly 5 in elevation and partly in longitudinal section through a roller and mountings there-

for, a portion of the roller being broken away and removed to condense the view.

Fig. 3 is a view similar to Fig. 2 but showing all of the parts in elevation.

Fig. 4 is an enlarged sectional view on the line 4-4 of Fig. 2.

Fig. 5 is an enlarged sectional view on the line 5-5 of Fig. 2.

Fig. 6 is a perspective view of a buffer and a retaining device extending therefrom.

In the drawings, where similar characters refer to similar parts throughout the several views, A designates a window casing including jambs B; C a roller shade comprising the shade proper D and roll or elongated cylindrical body E including the usual stub spindle F and key G of catch mechanism H at opposite ends of the body E; J a mounting for the end of roll E at 75 the stub spindle F; and, K a mounting for the end of the roll at key G.

Referring first to the disposition of the roller shade with respect to the casing A, it is contemplated to arrange the roller shade 80 and its mountings so as to be disposed between the jambs B in contra-distinction to arranging the roller shade over the face of the window casing where it is apt to destroy the architectural effect of said casing. 85 It is to be understood, however, that under certain conditions it might be desirable to provide abutments other than the jambs B and such may be accomplished without departing from the spirit or scope of my invention.

The roller E may be of any suitable type, such as are now in common use embodying the stub spindle F which is rigid with the roller and the key G, polygonal in cross-section, which is to be held rigid with the window casing, the main body of the roller being revoluble with respect thereto, the catch mechanism H including the usual ratchet member 7 and dogs 8 co-operating 100 therewith, said dogs being pivotally carried by the main body of the roller as by pins 9.

Referring now to the mounting J, it comprises a bearing designated generally by 10 and receiving the spindle F; a body 11 105 adapted to engage the jamb of the window casing A or other abutment; and, a device 12, such as an expansion spring, for yieldably forcing said body 11 in a direction away from bearing 10.

The bearing 10 preferably comprises a disk or plate 13 provided with an annular

ball-race 14; a coating plate or disk 15 provided with a ball-race 16 confronting the ball-race 14 and, in the example shown, provided with an annular flange 17 extending from its face opposite to the ball-race 16; 5 balls 18 in the races 14 and 16; and, a sleeve 19 joining the plates 13 and 15 but permitting rotation of the plate 13 independently of the plate 15. The sleeve 19 is concentrically arranged with respect to the ball-races and may extend through perforations 20 in the plates, the sleeve 19 receiving the stub spindle F.

As to the body 11, it may comprise a cup-like member 21 telescopically arranged with respect to the flange 17 of the plate 15 and a buffer 22, such as a disk of rubber or a composition including rubber at the end of cup-like member 21 opposite to plates 13 and 15.

20 The device 12 is accommodated within the shell or member 21 and in the example shown bears against plate 15 and the head of said member 21 having a tendency to move the body 11 in a direction away from plate 15 or bearing 10. Total separation of the body 11 from said bearing may be prevented by a device 23, in the form of a wire of substantial U-shape, the head 23' being embedded in buffer 22, with the arms extending through perforations 24 in body 21, lying laterally of the spring or device 12 and extending through perforation 25 in the plate 15, the ends of the arms being 35 turned over as at 26. The arms of device 25 are preferably arcuated as at 27 so as to be resilient. Therefore, upon compressing the spring 12 the arms 27 are arched permitting the buffer 22 to be manually moved 40 toward the bearing 10.

With reference to the mounting K, it is substantially like mounting J with the exception that the bearing 29 includes plates 30 and 31, the first-mentioned plate including a flange 32 which engages the pins 9 of dogs 8, while the plate 31 is provided with a key-way 33 to receive the key G, a sleeve 34 joining the plates 30 and 31, passing through a perforation 35 in plate 30 but provided 45 with arms or extension 36 which enter perforations 37 at opposite sides of the key-way 33. Thus the plate 30 is free to rotate with respect to plate 31 and move with the main body of the roll E, however, the key G polygonal in cross-section, fitting into the key-way 31 is held against rotation with respect to the roller E by the mounting K.

60 In assembling the mountings into operative relation to the roller E, the mounting J is arranged with the stub spindle F received by bearing 10 and with the plate 13 engaging the end portion of the roller E. The mounting K is arranged so that the key G extends into key-way 33 with the plates 30 65 engaging the other end portion of the roller

E. The bodies 11 are then moved toward their respective bearings so that the buffers 22 may be placed between the jambs B of the window casing A whereafter they are permitted to move away from one another 70 bringing the buffers into intimate contact with the jambs B, mounting the roller shade in operative relation to the window casing. As the shade proper D is drawn downwardly its margins may be alined with respect to the uprights of the window casing 75 by moving one or the other of the mountings upwardly or downwardly. It is to be observed that the mountings in no way defaces the window casing since there are no 80 metallic parts engaging or driven into the window casing.

Changes in details may be made without departing from the spirit or scope of my invention; but,

I claim:

1. In mountings for shades, the combination with a shade roller including the usual stub spindle rigid therewith and catch mechanism key at opposite ends, of a mounting 90 for said roller at that end carrying said stub spindle including a bearing for said spindle permitting the latter to rotate freely, a body movable toward and from said bearing along the axis of the said roller at the 95 exterior thereof, and a device for yieldably forcing said body in a direction away from said bearing; and, a mounting for said roller at that end carrying said key adapted to retain said key against rotation about the 100 axis of said roller.

2. In a mounting for shades, the combination with a shade roller including the usual stub spindle rigid therewith and catch mechanism key at opposite ends, of a mounting 105 for said roller at that end carrying said stub spindle permitting the latter to rotate freely; and a mounting for said roller at that end carrying said key including a bearing for the end of the roller adapted to retain said key against rotation, a body movable toward and from said bearing along the axis of said roller at the exterior thereof, and a device for yieldably forcing said body in a direction away from said bearing. 110

3. In mountings for shades, the combination with a shade roller including the usual stub spindle rigid therewith and catch mechanism key at opposite ends, of a mounting for said roller at that end carrying said 120 stub spindle including a bearing for said spindle permitting the latter to rotate freely, a body movable toward or from said bearing along the axis of said roll at the exterior thereof, and a device for yieldably forcing 125 said body in a direction away from said bearing; and, a mounting for said roller at that end carrying said key including a bearing for the said end of said roller adapted to retain said key against rotation, a body 130

movable toward and from said second bearing along the axis of said roller at the exterior thereof, and a device for yieldably forcing said second-mentioned body in a direction away from said second bearing.

4. In mountings for shades, the combination with a shade roller including the usual stub-spindle rigid therewith and catch mechanism key at the opposite ends, of a mounting for said roller at that end carrying said stub spindle including a bearing for said spindle permitting the latter to rotate freely, a body movable toward or from said bearing along the axis of the said roller at the exterior thereof, a device for yieldably forcing said body in a direction away from said bearing, and a device for preventing total separation of said body from said bearing.

5. In a mounting for shades, the combination with a shade roller including the usual stub spindle rigid therewith and catch mechanism key at opposite ends, of a mounting for said roller at that end carrying said stub spindle permitting the latter to rotate freely; and a mounting for said roller at that end carrying said key including a bearing for the end of the roller adapted to retain said key against rotation; a body movable toward and from said bearing along the axis of said roller at the exterior thereof, a device for yieldably forcing said body in a direction away from said bearing, and a device for preventing total separation of said body from said bearing.

6. In mountings for shades, the combination with a shade roller including the usual stub spindle rigid therewith and catch mechanism key at opposite ends, of a mounting for said shade roller at that end carrying said stub spindle including a bearing for said spindle permitting the latter to rotate freely, a body movable toward or from said bearing along the axis of said roller at the exterior thereof, a device for yieldably forcing said body in a direction away from said bearing.

bearing, and a device for preventing total separation of said body from said bearing; and a mounting for said roller at that end carrying said key including a bearing for the end of said roller adapted to retain said key against rotation, a body movable toward and from said second bearing along the axis of said roller at the exterior thereof, and a device for preventing total separation of said second-mentioned body from said second-mentioned bearing.

7. A roller shade mounting comprising in combination, two plates provided with confronting annular ball-races, a sleeve joining said plates but permitting one to rotate independently of the other; balls in said races about said sleeve, a buffer, and means for yieldably connecting said buffer with one of said plates.

8. A roller shade mounting comprising in combination, two plates provided with confronting annular ball races, one of said plates provided with an annular flange extending from its face opposite to its ball race; a sleeve joining said plates but permitting one to rotate independently of the other; balls in said races about said sleeve; a cylindrical shell telescopically arranged with respect to the said flange of said plate; a buffer carried by said shell at its end opposite to said plate; an expansion spring in said shell acting upon the same to yieldably move said buffer in a direction away from said plate; and, means for preventing total separation of said shell from said plate.

9. A shade roller mounting comprising in combination two plates provided with confronting annular ball races, one of said plates provided with a concentric key-way; a sleeve joining said plates but permitting one to rotate independently of the other; balls in said races about said sleeve; a buffer; and, means for yieldably connecting said buffer with the said plate provided with said key-way.

EUGENE M. STARN.
